UNITED STATES PATENT OFFICE

2,031,910

CONDENSER

Royal F. Sickles, Springfield, Mass.

Application April 12, 1935, Serial No. 16,027

5 Claims. (Cl. 175—41.5)

This invention relates to improvements in electrical apparatus and is directed more particularly to improvements in condensers which may be referred to as trimming condensers.

5 The principal object of the invention is the provision of a novel condenser construction which is particularly adapted for use in radio apparatus and the like although it is not necessarily limited to such use.

10 According to one special feature of the invention, the condenser is characterized by its simplicity of form and efficiency in operation while at the same time it is economical to manufacture.

15 According to another special feature of the invention the condenser is constructed and arranged for variation whereby its capacity is variable. That is to say, the capacity of my new condenser may be varied at will to vary the characteristics of the circuit in which it is connected and in order to obviate losses and the like the condenser is constructed in a novel manner.

20 One characteristic of the condenser is that it is compact so as to occupy but small space which is desirable in connection with radio apparatus. This is accomplished by a novel construction wherein a maximum of plate area is provided by obviating the common expedient of rivets and the locking of the plates in a novel manner eliminates the necessity for extraneous parts which tend to make the condenser bulky and expensive.

25 Many and various novel features and advantages of the invention not necessarily enumerated above will be hereinafter observed in the accompanying description of the preferred form thereof, reference being had to the accompanying drawing wherein:

30 Fig. 1 is a plan view of a condenser embodying the novel features of the invention;

35 Fig. 2 is a side elevational view of the condenser shown in Fig. 1;

40 Fig. 3 is an inverted plan view of the condenser shown in Fig. 1;

45 Fig. 4 is a perspective view of one of the condenser plates;

50 Fig. 5 is a plan view of one of the members for separating the plates of the condenser;

Fig. 6 is a perspective view of another of the condenser plates of the condenser shown in Fig. 1;

Fig. 7 is a similar view of a third plate of the condenser shown in Figs. 1, 2 and 3;

Fig. 8 is a view similar to Fig. 1 showing a condenser of the type shown in Figs. 1, 2 and 3 but embodying certain detail changes;

Fig. 9 is a perspective view of one of the plates of the condenser shown in Fig. 8;

Fig. 10 is a plan view of one of the members for separating the plates of the condenser shown in Fig. 8;

5 Figs. 11 and 12 are perspective views of other condenser plates of the condenser shown in Fig. 8;

Fig. 13 is an enlarged perspective view showing a terminal of one of the plates of the condenser; and

10 Fig. 14 is a sectional elevational view through the condenser shown in Fig. 1 to explain certain features of the invention.

15 Referring now to the drawing more in detail the invention will be fully described.

The condenser includes a body 2 which is preferably made from suitable insulating material such as ceramic or the like. The body has associated with it as will hereinafter appear a plurality of metallic condenser plates arranged in superposed relation with separating members therebetween which are non-metallic.

20 A central post 4 extends upwardly from the body and this as well as the body may be provided with openings such as 6 so that the condenser may be secured to a radio apparatus or the like. End projections or lugs 8 and 10 also extend upwardly from the body 2. Openings or slots such as 14 and 14' extend through the body 20 at either side of which parts such as 12 and 12' are provided, all as shown.

25 In the form of the condenser shown in Figs. 1, 2 and 3, there are a pair of separate condensers associated with the body. These are independently operable and the component parts of one only of them will be described. It will be understood that the body may carry any desired number of condensers.

30 A metallic condenser plate 18 as shown in Fig. 40 7 has a terminal part 20 which extends through the slot 14 of the body 2. An opening 22 in the central part thereof loosely receives the body of an adjusting screw 24 and a recess in the lower end of the plate is provided to form ears 28 which 45 span opposite sides of the lug such as 8 of the body member.

35 On top of the plate 18 there is a separating member or plate such as 30 which is preferably non-metallic. This has a central opening 32 50 for loosely receiving the body of screw 24 and its opposite ends are slotted as at 32 to provide ears 34 which are disposed at the sides of the projections 8 and 10. The plate 30 may be made of some such material as mica or the like. 55

An intermediate plate 40 is provided which overlies the insulating plate 30 just referred to and this plate 40 has a tail-piece or terminal part 45 for extending through the slot 14. An opening 44 is provided in the central part of the plate 40 for loosely receiving the screw 24 and one end portion of the plate is cut away at 42 as shown to provide ears 46 which are disposed at either side of a projection such as 10.

Over this plate 40 there is another separating member such as 30. A condenser plate 60 on the last-named separating member and uppermost in the condenser has a tail-piece or terminal portion 62 for extending through an opening such as 14 and a central opening 64 is provided to loosely receive the body of the screw 24. The end of the plate 60 is provided with a recess to form ears 66 which are disposed at opposite sides of projection 8 and the said plate is preferably non-flat and more or less spring-like.

The terminals of the plates in Figs. 4, 6 and 7 are shown as being flat but to explain an important feature of the invention reference is made to the enlarged view of Fig. 13 wherein it will be seen the terminals are offset or have portions in spaced planes for a purpose to be described.

With the plates 18, 40 and 60 and the separating plates 30 in the superposed relation described the terminals of the plates extend through the slots of the body member while the ears on the various plates are disposed at opposite sides of the lugs of the body. The uppermost plate is preferably non-flat, and others therebelow may be non-flat if desired, so that as the screw 24 is rotated in one direction or the other pressure is exerted on the uppermost plate which causes the offset portions of the terminals of the plates to abut opposite sides of the slots in which they are disposed. Washers 70 and 72 are disposed on the plate 60 against which the head of screw 24 bears. The washer 72 is preferably of insulating material while washer 70 may be of noninsulating material.

As the offset portions of the terminals abut the sides of the slots the plates are thereby held or locked against shifting and the ears disposed at opposite sides of the lugs co-operate therewith to hold and lock the plates against longitudinal and transverse relative shifting movement yet allowing the necessary up and down movements to effect the desired variation in capacity.

In this way the alternate plates and separating members are held securely in condenser forming relation which may be adjusted to a fine degree while the adjustment is not disturbed by vibrations and the like to which condensers of this type are subjected.

In the manner described the turning of the screw varies the capacity of the condenser and when used in circuits of various kinds wires may be connected to the terminal portions of the various plates projecting through the base member.

As a special feature it will be noted that the terminal portions of the plates of one condenser are spaced at a desirable distance from one another thereby to reduce losses and minimize capacity therebetween. This is not only desirable in devices of this type but contributes to the efficiency of the apparatus with which the device is used.

The form of the invention shown in Figs. 8 to 12 will now be described in detail.

In this form of the invention a base plate 80 is provided with a central boss 82 and end slots 84 and 84'. Slots 86 and 86' are also provided in

the base 80 as shown. In this form of the invention also the condenser structure may include two separate condensers which are substantially alike and therefore the elements forming one of the condensers only will be described.

An uppermost condenser plate 90 which is preferably more or less non-flat as shown has a terminal portion 92 at one end which is adapted to pass through the slot 84' and a guide portion 94 for insertion in the slot 84. A separating member or plate 96 preferably of mica or some equally suitable material has recesses 98 on its opposite ends which are adapted to receive the portions 92 and 94 of plate 90 whereby the said member plate is guided and held in its desired position relative to the plate 90 and the other plates constituting the condenser.

This member 96 lies just beneath the uppermost plate 90 and below the same there is an intermediate condenser plate such as 100 shown in Fig. 11. This plate 100 has a terminal 104' which extends through the slot 86' and a guide portion 104 which extends through the slot 86. Opposite ends of plate 100 are recesses as at 105 so that the end edges of the plate 100 are spaced from the parts 92 and 94 of the plate 90. Below this plate 100 there is a second separating member such as 96.

Lowermost and below the last-mentioned separating member there is a condenser plate 106 which has an upper terminal 108 and a lower terminal 110 the former of which extends through the slot 84' and the latter extending into the slot 84. An adjusting screw 112 passes through suitable openings in the plates 90, 96, 100 and 106, and its lower end is in threaded engagement with a nut at the lower side of the base plate after the manner shown in Fig. 3. A washer 114, similar to 70 and 72 already described, underlies the head of said screw.

The terminals 92, 104' and 108 of the plates 90, 100 and 106 which extend through the base 80 may be connected to a circuit and as in connection with the form of the invention previously described. Screw 112 is rotated in one direction or the other to vary the capacity of the condenser of which they are a part. The plates forming the condenser are gilded by the means described whereby it is possible to obtain very fine capacitative adjustments all of which is desired in condensers of this type, which are commonly used in association with delicate radio apparatus where the utmost accuracy in the characteristics of circuits is desired and necessary.

It is necessary to mention that the terminals 92, 104' and 108 of plates 90, 100 and 106 are offset similarly to the illustration in Figs. 13 and 14 for the functions already described.

While I have described the invention in great detail and with respect to a preferred form thereof, it is not desired to be limited thereto since many changes and modifications may be made therein without departing from the spirit and scope of the invention.

What it is desired to claim and secure by Letters Patent of the United States is:

1. A condenser of the class described comprising in combination, a base having spaced openings extending therethrough, alternate superposed condenser and separator plates on said base, the uppermost plate being curved and adapted to be depressed, terminals extending from said condenser plates through said openings and being offset to have portions in different

- planes engageable with opposite sides of said openings to hold said plates against shifting longitudinally and permitting up and down movements, the said plates being provided with openings therethrough, a washer on the uppermost plate and provided with an opening therethrough, and a screw extending through said openings threadedly engaging said base having its head bearing on said washer for depressing the uppermost plate.
5. A condenser of the class described comprising in combination, a base having spaced openings therethrough, alternate superposed condenser and separator plates between said openings, the uppermost plate being curved and springlike and adapted to be depressed, terminals on said condenser plates extending through the openings, which are offset to have portions in different planes within the openings bearing on opposite sides of the openings to prevent said plates from shifting longitudinally and permitting said plates to move towards and away from the base, the said plates being provided with openings therethrough, a washer on the uppermost plate provided with an opening therethrough, and a screw having its head bearing on the said washer and passing through the openings therein and threadedly engaging the base.
10. A condenser of the class described comprising in combination, a base having spaced lugs extending upwardly from a face thereof and provided with openings therethrough extending through the base at adjacent sides of the lugs, alternate superposed condenser and separator plates on said base between said lugs, the uppermost plate being curved and spring-like so as to be depressible, said plates provided with openings therethrough, a washer on the uppermost plate provided with an opening therethrough, a screw extending through said openings threadedly engaging said base with its head bearing on said washer, terminals extending through the openings of the base connected to the condenser plates, and ears provided on the separator plates at their ends disposed at opposite sides of the lugs.
15. A condenser of the class described comprising in combination, a base having spaced lugs extending upwardly from a face thereof and provided with openings therethrough extending through the base at adjacent sides of the lugs, alternate superposed condenser and separator plates on said base between said lugs, the uppermost plate being curved and spring-like so as to be depressible, said plates provided with openings therethrough, a washer on the uppermost plate provided with an opening therethrough, a screw extending through said openings threadedly engaging said base with its head bearing on said washer, terminals extending through the openings of the base connected to the condenser plates, and ears provided on the separator plates at their ends disposed at opposite sides of the lugs, the said terminals being offset to have parts in different planes in said openings bearing on opposite sides of said openings.
20. A condenser of the class described comprising in combination, a base, lugs in spaced relation extending upwardly from a face of the base and the base provided with openings therethrough at adjacent sides of said lugs, alternate superposed condenser and separator plates between the lugs on said base, the uppermost plate being curved from end to end, the said plates being provided with openings, a washer on the uppermost plate provided with an opening therethrough, a screw having its head bearing on the said washer and extending through said openings threadedly engaging said base, the separator plates being provided with slots on opposite ends forming spaced ears disposed at opposite sides of said lugs, and terminals connected to said condenser plates extending through the openings in the base having offset portions in said openings engaging opposite sides thereof.
25. A condenser of the class described comprising in combination, a base, lugs in spaced relation extending upwardly from a face of the base and the base provided with openings therethrough at adjacent sides of said lugs, alternate superposed condenser and separator plates between the lugs on said base, the uppermost plate being curved from end to end, the said plates being provided with openings, a washer on the uppermost plate provided with an opening therethrough, a screw having its head bearing on the said washer and extending through said openings threadedly engaging said base, the separator plates being provided with slots on opposite ends forming spaced ears disposed at opposite sides of said lugs, and terminals connected to said condenser plates extending through the openings in the base having offset portions in said openings engaging opposite sides thereof.
30. A condenser of the class described comprising in combination, a base, lugs in spaced relation extending upwardly from a face of the base and the base provided with openings therethrough at adjacent sides of said lugs, alternate superposed condenser and separator plates between the lugs on said base, the uppermost plate being curved from end to end, the said plates being provided with openings, a washer on the uppermost plate provided with an opening therethrough, a screw having its head bearing on the said washer and extending through said openings threadedly engaging said base, the separator plates being provided with slots on opposite ends forming spaced ears disposed at opposite sides of said lugs, and terminals connected to said condenser plates extending through the openings in the base having offset portions in said openings engaging opposite sides thereof.
35. A condenser of the class described comprising in combination, a base, lugs in spaced relation extending upwardly from a face of the base and the base provided with openings therethrough at adjacent sides of said lugs, alternate superposed condenser and separator plates between the lugs on said base, the uppermost plate being curved from end to end, the said plates being provided with openings, a washer on the uppermost plate provided with an opening therethrough, a screw having its head bearing on the said washer and extending through said openings threadedly engaging said base, the separator plates being provided with slots on opposite ends forming spaced ears disposed at opposite sides of said lugs, and terminals connected to said condenser plates extending through the openings in the base having offset portions in said openings engaging opposite sides thereof.
40. A condenser of the class described comprising in combination, a base, lugs in spaced relation extending upwardly from a face of the base and the base provided with openings therethrough at adjacent sides of said lugs, alternate superposed condenser and separator plates between the lugs on said base, the uppermost plate being curved from end to end, the said plates being provided with openings, a washer on the uppermost plate provided with an opening therethrough, a screw having its head bearing on the said washer and extending through said openings threadedly engaging said base, the separator plates being provided with slots on opposite ends forming spaced ears disposed at opposite sides of said lugs, and terminals connected to said condenser plates extending through the openings in the base having offset portions in said openings engaging opposite sides thereof.

ROYAL F. SICKLES.
